[57] CLAIM

The ornamental design for a beverage cup, as shown and described.

DESCRIPTION

FIG. 1 is a top perspective view of a beverage cup showing my new design;

FIG. 2 is a side elevational view thereof;

FIG. 3 is a top plan view thereof;

FIG. 4 is a bottom plan view thereof; and

FIG. 5 is an enlarged vertical sectional view taken substantially along the line 5—5 of FIG. 3 and shows most specifically the configuration of the beverage cup.

FIG. 1

FIG. 2

FIG. 4

FIG. 3
